(57) **CLAIM**

We claim the ornamental design for a bottle, as shown and described.

DESCRIPTION

FIG. 1 is an elevation view showing our new design from the front and right sides at a 45° rotation from the other elevation views;

FIG. 2 is front-elevation view thereof and the rear view is a mirror image thereof;

FIG. 3 is a top plan view thereof;

FIG. 4 is a bottom plan view thereof;

FIG. 5 is a right side-elevation view thereof; and,

FIG. 6 is a left side-elevation view thereof.

The broken lines in the drawings are included for the purpose of illustrating portions of the bottle that form no part of the claimed design.
